UNITED STATES PATENT OFFICE.

THOMAS H. GARLAND, OF CHICAGO, ILLINOIS.

VENTILATOR.

1,131,362.

Specification of Letters Patent.

Patented Mar. 9, 1915.

Application filed June 29, 1914. Serial No. 847,821.

To all whom it may concern:

Be it known that I, THOMAS H. GARLAND, a citizen of the United States, and a resident of Chicago, in the county of Cook and State 5 of Illinois, have invented certain new and useful Improvements in Ventilators, of which the following is a specification.

My invention relates to ventilators, particularly to that class to be used on traveling 10 vehicles, and is particularly desirable in structures where air is directed to flow across the mouth of an eduction passageway connected with the interior of the vehicle to be ventilated, particularly where cowl pas- 15 sageways are used for directing the air.

Where such passageways have considerable area there is a chance for formation of eddy currents which results in non-uniformity of air flow and a reduction in efficiency. This 20 is particularly true where the ventilator structures are curved and the air must flow from one level to another.

The main object of my invention is therefore to provide a construction which will 25 effect uniformity of flow through the passageways and this I accomplish by inserting tiers of partitions in the various passageways to vertically sub-divide such passageways. These partitions sub-divide the 30 entering air into streams which will flow uniformly through the sub-passageways in consequence of which the flow of air through the structure as a whole becomes uniform and the greatest efficiency results.

35 The various features of the invention are clearly illustrated on the accompanying drawings in which—

Figure 1 shows the end view of a ventilator adapted particularly for application to 40 deck type roofs, a section of such roof being shown, Fig. 2 is a front elevational view of the ventilator, Fig. 3 is a plan view thereof, Fig. 4 shows one end of the ventilator illustrating a modified arrangement, Fig. 5 is an end view of a ventilator adapted particularly for application to the arch type of 45 roofs of railway cars, a section of roof being shown, Fig. 6 is a front elevational view, and Fig. 7 is a plan view.

50 Referring to Figs. 1, 2 and 3, the ventilator housing comprises a lower wall or base 10, a top wall or roof 11 and an inner wall 12. The outer edges of the base and top walls are shortened, and connecting between 55 the end edges of these walls are the end

walls 13 and 13' which extend inwardly and then deflect gradually laterally and terminate in the vertical plane of the end edges of the inner wall 12. Also disposed between the base and top walls 10 and 11 are the 60 intermediate walls 14 and 14' which extend inwardly and then gradually deflect laterally and terminate at the ends of the inner wall 12. The walls 13 and 14, and 13' and 14' form cowl passageways 15 and 15', and the walls 14 and 14' together with the inner wall 12 form the eduction compartment or passageway 16, the base inner wall 12 having the opening 17 adapted for communicating with a suitable window opening 17' 70 in the deck of the car to which the ventilator is applied.

The ventilator thus far described operates substantially in the same manner as the ventilator disclosed in my Patent No. 75 874,320, issued December 17, 1907.

The ventilator is applied to the car roof with the entrance ends *e* and *e'* of the cowl passageways in the direction of travel of the car in order that when the car travels 80 in one direction the wind will enter the forward cowl in a direction longitudinal of the car and will be deflected gradually through the cowl to leave the cowl in a direction transverse of the car, the air being then deflected rearwardly across the mouth *m* of the eduction passageway 16 to create an eductive effect in said passageway which will result in withdrawal of air from the car through opening 17. The entrances *e* and *e'* of the 90 cowls are preferably of larger area than the outlets *o* and *o'* in order that the in-rushing air has its velocity increased to thus exert greater eduction effect at the mouth end. The outer faces of the walls 13 and 13' will 95 act as secondary cowls, the air striking the forward wall as the train travels and being deflected gradually from longitudinal direction to transverse direction relative to the car, the air after leaving the outer end of 100 the wall being deflected rearwardly to flow with the air from the main cowl passageway 15 across the eduction passageway mouth *m*.

I have found that where the cowls and 105 eduction passageway are of considerable area there is a chance for eddy currents and counter currents, the air tending to crowd to one part of the cowl passageway or eduction passageway. This is particularly true 110

where the ventilator structure follows a curved roof, and where the outer edges of the top and bottom walls are below the inner edges of these walls. The wind entering a 5 cowl passageway tends when deflected laterally to flow horizontally and will therefore crowd and concentrate toward the top of the ventilator leaving a space below that is inoperative. The same is true in the eduction passageway. I have found, however, 10 that by sub-dividing the passageways vertically a much more uniform distribution of air through the ventilator results and the efficiency is greatly increased. Such sub- 15 dividing is accomplished by inserting a plurality of partitions 18, 18' in the respective cowl passageways, and partitions 19 in the eduction passageway. As shown in Figs. 1 to 4, these eduction passageway partitions 20 could extend inwardly to the rear wall 12. With these partitions much more uniform air distribution results through the passageways, the air entering the large inlet to the advancing cowl passageway being divided 25 equally among the sub-passageways and traveling uniformly therethrough, the lower section of the ventilator being thus utilized with substantially the same efficiency as the upper part. The same is true in the eduction 30 passageway, the air entering through the inlet from the car being divided equally through the sub-passageways and flowing uniformly therethrough without congestion at any part thereof. The bottom and top 35 walls 10 and 11 and the partition walls 18, 18' and 19 could extend horizontally and at right angles to the inner wall 12 but in order that rain, cinders, and the like will be shed from the structure, these walls preferably 40 incline downwardly as shown. Instead of being raised from the roof as shown the ventilator could rest on the roof and follow the curvature thereof.

In order to fully utilize the cowl effect 45 of the end walls 13 and 13' and to get uniform air distribution, they could also be sub-divided by the extended ends 11' and 10' of the top and base walls and by the application of partition strips 20, as shown in Fig. 50 4. The air then striking the end wall will be uniformly distributed through the various sub-passageways to coöperate with the air currents from the adjacent cowl sub-passageways. Preferably the sub-dividing 55 walls of all the passageways are in horizontal alignment.

The ventilator shown in Figs. 5 to 7 is particularly adaptable for application to the arch type of roof. The construction is substantially the same as that in Figs. 1 to 4 except that the inlet opening 21 is provided in the base wall 10 for coöoperating with the opening 22 through the roof of the car. Instead of extending the partition walls 18, 65 18' and 19 entirely through the cowls and

eduction passageway as in Figs. 1 to 4, they could be extended only through the outer ends thereof. The inner edges of these partitions are preferably deflected upwardly to form flanges 23 for preventing entrance of 70 cinders, rain, snow, etc. A set of louvers 24 may also be inserted in the ventilator in front of the eduction inlet 21 to the ventilator, and a grating 25 may be applied to the car ceiling over the opening 22.

The operation of the ventilator of Figs. 5 to 7 is the same as that of the ventilator shown in Figs. 1 to 4, the in-coming air being sub-divided to flow uniformly through the ventilator.

I thus provide a very efficient ventilator which utilizes to the fullest extent the air flowing therethrough and which therefore possesses great efficiency.

The structure is of simple and inexpensive 85 design and can be quickly and readily applied to the vehicle to be ventilated.

I do not confine myself to the exact structures shown as changes and modifications may be made which would still come within 90 the scope of the invention.

I claim the following:

1. A ventilating structure comprising a housing curved transversely downwardly and having a transverse eduction passageway, a cowl adjacent each end of said passageway for directing air across the outlet of said passageway, said cowls being vertically sub-divided.

2. A ventilating structure comprising a 100 housing curved transversely downwardly and having a transverse eduction passageway, a cowl adjacent each end of said passageway for directing air across the outlet of said passageway, said eduction passageway 105 and cowls being vertically sub-divided.

3. A ventilator structure comprising a laterally extending housing having passageways therethrough transverse to the direction of travel of the wind, said passageways 110 deflecting vertically and tending to shift the wind from one level to another in its passage therethrough, and partitions vertically sub-dividing said passageways and extending in the same general direction as the walls thereof whereby the wind is forced to travel uniformly through said passageways throughout the extent thereof.

4. A ventilator structure comprising a laterally extending housing having an eduction 120 passageway, a cowl at one end of the housing having its entrance facing the wind and having its outlet adjacent the eduction passageway outlet whereby wind passing through the cowl will be deflected across the eduction 125 passageway outlet, said housing deflecting vertically and thereby tending to shift the wind from one level to another and thereby causing concentration of the wind toward the wall of the housing tending to effect such 130

shift of the wind, and partitions vertically sub-dividing said passageway and cowl and extending in the same general direction as said passageway whereby the wind will be prevented from concentrating and will be forced to flow uniformly through the passageway and cowl and to flow in uniform density from the passageway and cowl.

In witness whereof, I have hereunto subscribed my name this 26 day of June, A. D., 1914.

THOMAS H. GARLAND.
